Primary Examiner — Catherine A Tuttle(74) *Attorney, Agent, or Firm* — Haim M. Factor(57) **CLAIM**

The ornamental design for an immersible elephant water pump, as shown and described.

DESCRIPTION

FIG. 1 is a frontal perspective view of the new design;

FIG. 2 is a right view thereof;

FIG. 3 is a left view thereof;

FIG. 4 is a front view thereof;

FIG. 5 is a back view thereof;

FIG. 6 is a top view thereof; and,

FIG. 7 is a bottom view thereof.

The appearance of any portion of the article between the symbolic break lines forms no part of the claimed design.

1 Claim, 7 Drawing Sheets(56)
